UNITED STATES PATENT OFFICE

165,056

PAPER KNIFE

John L. Day, Jr., Portland, Oreg.

Application December 7, 1949, Serial No. 6,470

Term of patent 7 years

(Cl. D74—1)

To all whom it may concern:

Be it known that I, John L. Day, Jr., a citizen of the United States of America, residing at Portland, in the county of Multnomah, State of Oregon, have invented a new, original, and ornamental Design for a Paper Knife, of which the following is a specification, reference being had to the accompanying drawing, forming part thereof.

In the drawing.

Fig. 1 is an obverse view of the paper knife showing my new design;

Fig. 2 is a side view of the paper knife; and Fig. 3 is a reverse view of the paper knife.

I claim:

The ornamental design for a paper knife, as shown.

JOHN L. DAY, JR.
